(57) **CLAIM**

The ornamental design for an aerator for taps, as shown and described.

DESCRIPTION

1.1 is a front and left side perspective view of an aerator for taps, showing our new design;

1.2 is a bottom and right side perspective view thereof;

1.3 is a front elevational view thereof;

1.4 is a side view thereof;

1.5 is a top view thereof; and

1.6 is bottom view thereof.

The broken lines are for the purpose of illustrating portions of the aerator for taps and form no part of the claimed design.
